UNITED STATES PATENT OFFICE.

WALTER J. PHELPS, OF SALEM, OHIO.

SOLDERING-MACHINE.

SPECIFICATION forming part of Letters Patent No. 439,762, dated November 4, 1890.

Application filed June 5, 1890. Serial No. 354,363. (No model.)

To all whom it may concern:

Be it known that I, WALTER J. PHELPS, a citizen of the United States, residing at Salem, in the county of Columbiana and State of Ohio, have invented a new and useful Machine for Soldering Cylindrical Tin Cans, of which the following is a specification.

This invention relates to machines for soldering cylindrical tin cans; and it has for its object to provide a device of this class which shall be simple, durable, and efficient, and which shall be so arranged as to permit two workmen to use the machine at the same time, one of said workmen being provided with tools for soldering the side seams while the other secures the bottoms upon the cans.

With these ends in view the invention consists in details of construction to be herein-after more fully described, and particularly pointed out in the claims.

In the drawings, Figure 1 is a perspective view of a can-soldering machine embodying my improvements. Fig. 2 is a longitudinal vertical sectional view of the same. Fig. 3 is a vertical transverse sectional view. Fig. 4 is a rear view. Fig. 5 is a detail view of the slotted supporting-plate.

Like numerals of reference indicate like parts in all the figures.

1 designates the base, which consists of a metallic plate having an opening 2 formed therein. Mounted upon the said base is a rectangular casing, which is composed of an outer and an innershell, which are designated, respectively, 3 and 4. Between the said shells is a space 5, which may be left open, or which, if desired, may be packed with asbestos or with any suitable non-conducting material. The bottom of the inner casing 4 is provided with an opening 6, in front of which it has a transverse slot 7. The bottom of said casing is also provided with a series of longitudinal ribs or flanges 8, the function of which will be presently described. The rear end of the shell 4 is open and is made flared, as shown, the said flaring ends being engaged by a flange 9, which depends from the rear edge of the outer shell 3. The latter is provided with lugs 10 to receive screws or bolts, by means of which it is secured to the base, thus serving to retain the inner shell in its proper position upon the latter.

The top or upper side of the outer shell 3 is provided with the melting-pot 11, and the upper surface of the top of the said shell, which is designated by 12, is made to slant from its outer edge down to the edge of the said pot. This is for the purpose of preventing the molten metal contained in the latter from overflowing, it being necessary in practice to keep the said pot about level-full of the solder. At or near the upper edge of the said pot is formed a shoulder 13, which serves to support a plate 14, having a slot 15 formed therein. Upon the upper side of said plate adjacent to the rear edge of the slot is formed a lip 16, which may or may not be tinned over. The upper side of the plate 14 is covered with a coating 17 of asbestos, which serves to prevent the upper surface from being tinned over when the solder would be liable to flush up over the surface of the can when the latter is being operated upon.

The shell or casing 3 is provided with laterally-extending lugs 18, supporting, respectively, a guide 19 and a wiper 20. The former consists of a longitudinally-slotted plate provided at its inner end with a beveled head or enlargement 21. The wiper, which is of a construction shown and described in Letters Patent of the United States issued to me on the 17th day of December, 1889, No. 417,682, is provided with a piece of asbestos cloth 22, held detachably between the clamping-jaws 23. The guide 19 and the wiper 20 are both mounted adjustably and detachably upon the lugs 18 by means of bolts or set-screws or in any other suitable and convenient manner. The said devices also serve to press upon the ends of the plate 14, thus retaining the latter in any position to which it may have been placed.

The melting-pot is provided with an abutment 24, upon which is mounted an upright 25, to the upper end of which a frame 26 is pivotally attached by means of a bolt or in any other convenient manner. The said frame serves in practice to support the can which is being operated upon, and being made of open-work, as shown, it permits superfluous rosin to drop through, instead of accumulating upon the said plate, where it would to some extent interfere with the operation of the device.

28 designates a damper or deflector, which extends through the slot 7 in the bottom of the inner shell 4 in an upward and forward direction. In practice the burner, which supplies the necessary heat, extends through the opening 6, which is directly below the melting-pot. The said deflector may, when desired, be pushed up between the burner and the bottom of the melting-pot, thus preventing the solder from burning in the event that for a period it shall not be desired to utilize the said melting-pot.

The damper or deflector 27 is provided with a handle 28, by means of which it may be conveniently manipulated. Suitable means may also be provided for retaining the said deflector in any position to which it may be adjusted.

From the foregoing description, taken in connection with the drawings hereto annexed, the operation and advantages of my invention will be readily understood by those skilled in the art to which it appertains. The tools which are used for soldering the side 25 seams are placed upon the bottom of the inner shell 3, resting upon the ridges or flanges 8, which form a grate to support the said tools. The workman stationed at one side of the machine solders the side seams and passes 30 the cans to the next workman, who places the bottoms in position, and, placing the can upon the supporting-frame 26 with its lower edge resting in the slot 15 in plate 14, rotates the can, thus causing the bottom seam to be 35 soldered.

In this class of devices the casing of the machine, or "stove," as it is commonly called, is usually made of only a single thickness of metal. Owing to this, it soon becomes very 40 hot, rendering it exceedingly uncomfortable for the operator, who is obliged to occupy a position in close proximity to the said stove. By my improvement the space between the inner and outer shells, which may either be a 45 dead-air space or packed, as herein described, with non-conducting material, keeps the outer shell comparatively cool.

Can-soldering machines have heretofore been constructed in which a slotted supporting-plate has been used to guide and support the can during the operation. The objection, however, has existed that this strip or plate will soon become tinned over on its entire upper surface, thereby causing the solder to 50 flush up over the sides of the can, thus incurring a waste of material and making less perfect work. By my improvements these 55 defects are thoroughly avoided. The combination with the device of the wiper herein 60 described also serves to make more perfect work and to avoid unnecessary waste of material.

If for any reason it shall be desired to temporarily suspend the use of the melting-pot, the deflector may be moved into position under the latter, and the solder contained therein thus be prevented from burning.

While I have in the foregoing described what I consider to be a simple and efficient construction of my invention, I desire it to be understood that I reserve the right to any changes and modifications in the construction of the same which may be resorted to without departing from the spirit of my invention.

Having thus described my invention, I claim—

1. In a can-soldering machine, the combination of the inner shell or casing, the bottom of which is provided with an opening for the passage of the burner, the outer shell or casing having the melting-pot in its upper side, a slotted supporting-plate arranged transversely across the melting-pot and having a covering of asbestos, and an upright arranged adjacent to the melting-pot and having a hinged supporting-frame, substantially as set forth.

2. In a can-soldering machine, the combination, with the inner shell having an open flaring rear end and the bottom of which is provided with an opening for the passage of the burner, of an outer shell or casing inverted over the inner shell having the melting-pot formed therein, having a depending lip at its open rear end and provided with laterally-extending lugs having perforations to receive bolts or screws, by means of which it may be secured to a suitable base-plate, substantially as set forth.

3. The combination, with the inner shell having the flaring rear end, of the outer shell having a depending lip at its upper rear edge, substantially as and for the purpose set forth.

4. In a can-soldering machine, the herein-described melting-pot, having an abutment and extending on both sides of said abutment, in combination with the upright mounted upon said abutment and having a hinged supporting-frame at its upper end, substantially as set forth.

5. In a can-soldering machine, the herein-described shell or casing, having the melting-pot, the upper side of said shell or casing being made slanting from its outer edges to the edges of the melting-pot, substantially as set forth.

6. In a can-soldering machine, the shell or casing having the melting-pot provided with shoulders on opposite sides near its upper edge, in combination with the slotted supporting-plate mounted adjustably upon said shoulders, and the guide and wiper pressing upon said supporting-plate and retaining it in position, substantially as set forth.

7. In a can-soldering machine, the combination, with the melting-pot, of a slotted supporting-plate provided with an upwardly-extending lip adjacent to the front edge of the slot, and having on its upper side a coating or covering of asbestos, substantially as and for the purpose set forth.

8. In a can-soldering machine, the combi-

nation of the casing having the melting-pot, the slotted supporting-plate, and the guide and wiper mounted adjustably upon said casing over the plate and adapted to hold it down, substantially as and for the purpose set forth.

9. In a can-soldering machine, the casing consisting of an inner shell having a transverse slot and an opening at the bottom for the passage of the burner, and an outer shell inverted over the inner shell and having the melting-pot at the top, combined with an adjustable damper or deflector extending through the slot in the bottom of the inner shell and adapted to be interposed between the burner and the melting-pot, substantially as and for the purpose set forth.

10. A can-soldering machine comprising an inner shell open at its rear end for the reception of hand-soldering tools and provided in its bottom with an opening for the passage of the burner, an outer shell or casing having the melting-pot, an upright having a hinged supporting-frame, a slotted supporting-plate

arranged transversely across the melting-pot 25 and having a covering of asbestos, and the guide and the wiper mounted adjustably upon the upper side of the outer casing and serving to retain the slotted supporting-plate in position, substantially as set forth. 30

11. The combination of the outer shell or casing having the melting-pot and having its upper surface made slanting from its outer edges to the edges of the pot, the upright having the hinged supporting-frame, the slot- 35 supported supporting-plate arranged transversely across the melting-pot and having a covering of asbestos, and the guide and the wiper mounted adjustably upon the said upper side of the outer casing, substantially as set forth. 40

In testimony that I claim the foregoing as my own I have hereto affixed my signature in presence of two witnesses.

WALTER J. PHELPS.
